UNITED STATES PATENT OFFICE.

EDWIN R. TALLEY, OF ALGONA, IOWA.

NUT-LOCK.

1,159,618.

Specification of Letters Patent.

Patented Nov. 9, 1915.

Application filed October 9, 1913, Serial No. 794,251. Renewed July 24, 1915. Serial No. 41,800.

To all whom it may concern:

Be it known that I, EDWIN R. TALLEY, a citizen of the United States, residing at Algona, in the county of Kossuth and State 5 of Iowa, have invented certain new and useful Improvements in Nut-Locks, of which the following is a specification.

This invention relates to new and useful 10 improvements in nut locks, and the primary object is to provide a device of this character which will positively lock a nut in place to prevent casual disengagement thereof in use.

A further object of the invention resides 15 in providing a key on the nut adapted for engagement with a slot in the bolt, and a still further object resides in providing an improved means in connection with the nut for retaining the key out of view when same 20 is effectively disposed.

Still another object of the invention is to provide a device which is simple and durable in construction, inexpensive to manufacture and one which is very efficient and 25 useful in operation.

With these and other objects in view, my 30 invention consists in the novel features of construction, combination and arrangement of parts as will be hereinafter referred to and more particularly pointed out in the specification and claims.

In the accompanying drawing forming a part of this application:

Figure 1 is a perspective view of a device 35 embodying my improvements. Fig. 2 is a vertical section therethrough, partly in elevation. Fig. 3 is a perspective view of a nut embodying my improvements and disclosing parts separated. Fig. 4 is a horizontal section through the device applied.

In describing the invention I shall refer to the drawing, in which similar reference characters designate corresponding parts throughout the several views, and in which 45 1 indicates a bolt of the usual or any preferred type having the longitudinal slots 2 in the threaded portion thereof at diametrically opposite points thereon. Adapted for engagement with the threaded portion of 50 the bolt is a nut 3 of hexagonal or other design, one face of which has a portion or strip removed therefrom to form a separable plate 4. This plate, it will be understood, when applied to the referred-to face of the

nut, will complete the formation of the 55 latter.

Extending through the nut from the face having the strip removed therefrom to the bore of the same is a threaded channel 5 with which is engaged a screw or threaded key 6. 60 The outer end of the channel 5 is chamfered so as to receive the head of the screw 6 in countersunk relation therein, and when the head is so positioned the end of the screw is adapted to be received in one of the slots 2 of 65 the bolt. From this construction it will be seen that after the nut has been properly turned home on the bolt the same is positioned to permit the channel 5 to register with a slot 2 in the bolt. The screw may then be 70 introduced through the nut to obviously lock the latter in its effective position on the bolt.

In order to prevent the casual disengagement of the screw 6 and also to hide the same from view, I provide a means for removably supporting the removed plate or strip 4 in position on the face of the nut from which same is removed. To this end the last referred to face of the nut is provided with a threaded opening 7 adjacent 80 one corner thereof and the plate 4 is provided with an opening 8 adapted to register with the opening 7 when the plate is properly applied on the nut. An additional screw 9 is adapted for introduction through 85 the opening 8 to be engaged with the threaded opening 7 whereby to pivotally support the plate 4 on the nut. In order to limit the swinging movement of the plate on the nut in one direction, the one face of the nut is 90 provided with a cavity 10, the inner wall of which is beveled, while the inner face of the plate 4 is provided with a projection or lug 11 adapted to be received in said cavity. The one end of the projection, contacting 95 with the one wall of the cavity, obviously limits the swinging movement of the plate 4, retaining the latter in such position as to complete the formation of the nut proper.

When it is desired to disengage the nut, the plate 4 must first be raised or swung on its pivot, so that engagement may be had with the screw 6 whereby to disengage the latter from the bolt. The nut may be removed as usual.

From the foregoing description of the construction of my improved device the operation thereof will be readily understood,

and it will be seen that I have provided a device which is simple and durable in construction, inexpensive to manufacture and one which will be very efficient and useful in operation.

What I claim is:

1. The combination with a bolt having a longitudinal slot in the threaded portion thereof; of a nut having a transverse opening therein, a member inserted in the transverse opening of a nut for engagement with the slot in the bolt to lock the former on the latter and a plate pivoted to one face of said nut to conceal said member, said plate covering the entire face of the nut.
2. The combination with a bolt having a longitudinal slot in the threaded portion thereof; of a nut having a transverse opening therein terminating at its outer end in one face of the nut, the last mentioned face of said nut varying in size from the other faces thereof, a member inserted through the opening of the nut to engage said slot and secure the nut on the bolt, and a plate pivotally applied to the last-mentioned face of

said nut to conceal said member and forming a face on the nut of equal size to the other faces of said nut.

3. The combination with a bolt having a longitudinal slot therein; of a nut having a transverse opening therein terminating at its outer end in one face of the nut, said last mentioned face varying in size from the other faces of said nut, a member inserted through said opening to engage said slot and secure the nut on the bolt, a plate forming a complete face for the nut pivotally applied to the last mentioned face of said nut to conceal the member therein, the face formed by such plate being equal in size to the other faces of the nut and means to limit the pivotal movement of the plate on the nut.

In testimony whereof I affix my signature in presence of two witnesses:

EDWIN R. TALLEY.

Witnesses:

EDMUND C. TESSMAN,
Jesse L. BOVAR.
